UNITED STATES PATENT OFFICE.

JOHN W. SMITH, OF NORMAL, ILLINOIS.

NUT SHELTER.

Application filed September 28, 1928. Serial No. 308,919.

The invention provides an implement which greatly facilitates the removal of the meat, or kernel, from soft shell nuts, such as English walnuts, pecans and Brazil nuts, without breaking the edible part into small pieces.

The invention contemplates a blade, embodying a head and a shank, and coacting nibs or beaks projecting from the head and adapted to receive the shell between them, whereby a turning of the device results in a stripping or breaking away of the shell from the kernel.

While the drawing illustrates a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawing hereto attached, in which:—

Figure 1 is a perspective view illustrating an application of an embodiment of the invention.

Figure 2 is a front view of the device.

Figure 3 is an edge view thereof.

Corresponding and like parts are referred to in the following description and designated in the several views of the drawing by like reference characters.

The implement consists of a metal blade embodying a shank 1 and a head 2. The end of the shank opposite the head 2 is beveled, as indicated at 3, to conform to the hand when the device is gripped, thereby preventing any part projecting beyond the side of the hand in line with the little finger and opposite the thumb. The head 2 projects beyond the sides of the shank 1 and is adapted to be gripped between the thumb and the forefinger of the hand to enable a turning of the device in the act of removing the shell from the nut. Nibs or beaks 4 and 5 project outwardly from the head 2 in line with the shank 1 and curve laterally in the same direction, as indicated most clearly in Figure 3 of the drawing. The part 5 is in the form of a

single curve, whereas the part 4 presents the outline of a compound curve, as indicated most clearly in Figure 3 of the drawing. 55 The confronting edges of the nibs or beaks 4 and 5 are spaced apart, as indicated at 6, to provide clearance for the shell to be pried away from the nut, as indicated most clearly in Figure 1 of the drawing. A point 7 projects laterally from the extremity of the nib or beak 4 and is adapted to engage the inner side of the shell which is received between the point 7 and the nib or beak 5. The edge of the part 5 bordering upon the space 6 is 65 toothed, as indicated at 8, to make positive engagement with the outer side of the shell and prevent slipping when turning the device to pry the shell away from the nut. In the preferable construction the device is formed 70 from sheet steel of suitable gauge and may be finished in any manner.

In practice the nut is cracked to admit of the point 7 reaching and engaging the inner side of the shell after which the device is 75 turned to pry the shell outwardly away from the meat. This operation is repeated until the shell is completely removed thereby resulting in obtaining the kernel in its entirety without any breaks. This obviates the necessity of picking the meat from the shell or the 80 necessity of repeated cracking in order to obtain the meat and which generally results in breaking of the kernel into small pieces.

Having thus described the invention, I 85 claim:

1. An implement for removing the shell from a pecan or analogous nut, the same comprising a blade having beaks projecting therefrom and adapted to receive the shell of the 90 nut therebetween to be removed by a prying action.

2. An implement for removing the shell from a pecan or analogous nut, the same comprising a blade having complementary beaks 95 projecting therefrom and curved in their length and spaced to receive the shell therebetween, one of the beaks having a terminal point projecting towards the companion beak to engage the inner side of the shell to be 100 pried from the nut.

3. A nut shelling implement comprising a blade having coacting beaks projecting therefrom and curving laterally in the same

direction and spaced to receive the shell there-
between, the inner edge of one of the beaks
being toothed and the companion beak ter-
minating in a point projecting toward the
toothed beak.

4. A nut shelling implement comprising a
blade including a shank and a head, and hav-

ing coacting beaks projecting from the head
in line with the shank and curving laterally
in the same direction, one of the beaks termi-
nating in a point.

In testimony whereof I affix my signature.

JOHN W. SMITH. [L. s.]
